HYDRAULIC CHAIR FOR HAIRDRESSERS OR THE LIKE

Leopold S. Romito, Ravenna, Ohio

Application May 11, 1955, Serial No. 35,931

Term of patent 14 years

(Cl. D15—3)

FIG. I.

FIG. 2.

Figure 1 of the drawing is a front corner perspective view of a hydraulic chair for hairdressers or the like in its lowermost position showing my new design.

Figure 2 is a rear corner perspective view of the same chair in an elevated position.

I claim:

The ornamental design for a hydraulic chair for hairdressers or the like, as shown.
